US0D1007517S

(12) **United States Design Patent** (10) **Patent No.:** **US D1,007,517 S**
(45) **Date of Patent:** **** Dec. 12, 2023**

(54) **STAND FOR A COMPUTER MONITOR**

(71) Applicant: **LG ELECTRONICS INC.**, Seoul (KR)

(72) Inventors: **Eunbong Lee**, Seoul (KR); **Daihyung Ryu**, Seoul (KR)

(73) Assignee: **LG ELECTRONICS INC.**, Seoul (KR)

(**) Term: **15 Years**

(21) Appl. No.: **35/515,491**

(22) Filed: **Apr. 26, 2022**

(80) **Hague Agreement Data**

Int. Filing Date: **Apr. 26, 2022**

Int. Reg. No.: **DM/220594**

Int. Reg. Date: **Apr. 26, 2022**

Int. Reg. Pub. Date: **Oct. 28, 2022**

(30) **Foreign Application Priority Data**

Nov. 12, 2021 (KR) 30-2021-0054030

(57) **CLAIM**

The ornamental design for a stand for a computer monitor, as shown and described.

DESCRIPTION

1. Stand for a computer monitor

1.1 : Perspective

1.2 : Rear perspective view

1.3 : Front

1.4 : Back

1.5 : Left

1.6 : Right

1.7 : Top

1.8 : Bottom

1.9 : Rear perspective view showing a state of use with a monitor

The broken lines depict portions of the article that form no part of the claimed design; the broken lines in Reproduction 1.9 depicting a monitor represent environmental subject matter that forms no part of the claimed design.

1 Claim, 9 Drawing Sheets
